UNITED STATES PATENT OFFICE

145,912

DESIGN FOR A RADIO SPEAKER GRILLE OR SIMILAR ARTICLE

Leland Geo. Stone, Fort Wayne, Ind., assignor to The Magnavox Company, Fort Wayne, Ind., a corporation of Delaware

Application December 14, 1944, Serial No. 116,899

Term of patent 14 years

(Cl. D26—14)

To all whom it may concern:

Be it known that I, Leland Geo. Stone, a citizen of the United States, residing at Fort Wayne, in the county of Allen, State of Indiana, have invented a new, original, and ornamental Design for Radio Speaker Grille or Similar Article, of which the following is a specification, reference being had to the accompanying drawings, forming part thereof.

In the drawings:

I claim:

The ornamental design for a radio speaker grille or similar article, substantially as shown.

LELAND GEO. STONE.
